INVENTOR
John A. Peer,

BY Edwin H. Farmer, HIS ATT'Y

UNITED STATES PATENT OFFICE.

JOHN A. PEER, OF BROOKLYN, NEW YORK, ASSIGNOR TO THE PEER MANUFACTURING COMPANY, OF SAME PLACE.

KNIFE-SHARPENER.

SPECIFICATION forming part of Letters Patent No. 465,880, dated December 29, 1891.

Application filed May 19, 1891. Serial No. 393,345. (No model.)

To all whom it may concern:

Be it known that I, JOHN A. PEER, of Brooklyn, Kings county, and State of New York, have invented a certain new and useful Improvement in Knife-Sharpener, of which the following is a specification.

The object of this improvement is to provide a simple, cheap, and efficient sharpener for table-knives and analogous devices.

1. I will describe a knife-sharpener embodying my improvement, and then point out the novel features in claims.

In the accompanying drawings, Figure 1 is a top view of a knife-sharpener embodying my improvement, with a certain part removed to exhibit other parts. Fig. 2 is a side view thereof. Fig. 3 is a central longitudinal section.

Similar letters of reference designate corresponding parts in all the figures.

2. A designates the base piece or frame.

B C designate blocks or pieces of material suitable for sharpening table-knives and like devices. They are arranged opposite to each other and are severally provided with a number of projections or tongue-like portions *b c*, which are inclined downwardly. The projections or tongue-like portions of each of these blocks or pieces B C are arranged opposite the spaces between those of the other one of said blocks or pieces, and it is intended that the blocks shall be so set that the lower portions of the projections or tongue-like portions of the two blocks shall overlap. Preferably the projections or tongue-like portions will be rounded at their upper extremities.

3. The block B has its body or main portion fitted to a recess *a*, formed in the base piece or frame A and may be adjusted lengthwise thereon, and, when adjusted, fastened in position by any suitable means—as, for example, by set-screws *a'*, passing through the sides of the base piece or frame and impinging against the sides of the block B.

4. From the body or main portion of the block B a portion is offset so as to extend over the top of the base piece or frame A. The upper surface of this offset portion of the block B may be used as a hone.

5. The block C is fitted to a recess *a'*, formed in the base piece or frame A, and is adapted to slide lengthwise thereon. It is forced to-

ward the block B by means of a spring D, and it may be adjusted away from the block B by means of a screw E. As here shown, the screw is provided at its inner end with a head 55 and the block C with a notch, whereby the block may be engaged with the screw. The screw is shown as extending through the adjacent end of the base piece or frame A and as having a nut *e* applied to it beyond the 60 base piece or frame A. The spring D is shown as surrounding the screw E between the block C and the opposite end of that recess in the base piece or frame A which is adjacent to the block C. A cap-piece *a'* is arranged over 65 the recess of the base piece or frame, in which the block C works. It may be fastened in place by screws.

Obviously both the blocks may be removed at pleasure.

70 Obviously by manipulating the nut *e* the block C may be drawn away from the block B against the resistance of the spring D, and by turning the nut in the other direction the spring would be permitted to force the block 75 C toward the block B. Obviously the block C is held in position in such manner as to be free to yield away from the block B. Owing to this, a knife or analogous device may be inserted between the upper portions of the 80 projections or tongue-like portions of the blocks B C, forced downwardly between the same, and moved back and forth while between them.

85 The base piece or frame may be made of any suitable material—as, for instance, metal—and the blocks B C may be made of any material. Preferably their projections or tongue-like portions *b c* will be made of emery, and the hone portion of the block B will be made of such material as is ordinarily employed for 90 hones.

95 By my improvement I produce a very simple, cheap, and efficient sharpener for knives and like devices, in which one of two blocks will have a sliding movement relatively to the other, so that the two blocks will be adaptable to a knife or like device inserted between them.

100 What I claim as my invention, and desire to secure by Letters Patent, is—

1. In a sharpener for knives and like devices, the combination of a base piece or

frame and two blocks having projections or tongue-like portions inclined downwardly and arranged so that the projections or tongue-like portions of each block will be opposite the spaces between those of the other, so that they may overlap the latter, and one of said blocks being constructed to slide along the base piece or frame toward and from the other block, substantially as specified.

10 2. In a sharpener for knives and like devices, the combination of a base piece or frame, two blocks having projections or tongue-like portions inclined downwardly and arranged so that the projections or tongue-like portions of each block will be opposite the spaces between those of the other, so that they may overlap the latter, and one of said blocks being constructed to slide along the base piece or frame toward and from the other block, and a spring for adjusting the sliding block toward its fellow, substantially as specified.

15 3. In a sharpener for knives and like devices, the combination of a base piece or frame, two blocks having projections or tongue-like portions inclined downwardly and arranged so that the projections or tongue-like portions of each block will be opposite the spaces between those of the other, so that they may overlap the latter, and one of said blocks being constructed to slide along the base piece or frame toward and from the other block, a spring for adjusting the sliding block

toward its fellow, and a screw for drawing the sliding block away from its fellow, substantially as specified.

4. In a sharpener for knives or like devices, the combination of a base piece or frame having two recesses, a block having a body or main portion fitting in one of the recesses and an offset portion extending over the base piece or frame and forming a hone, and a sliding block arranged opposite to the block aforesaid, said blocks having projections or tongue-like portions which are inclined downwardly and so arranged that the projections or tongue-like portions of each block will be opposite the spaces between those of the other block, substantially as specified.

5. In a sharpener for knives and like devices, the combination of a base piece or frame, two blocks having projections or tongue-like portions downwardly inclined and arranged so that those of each block will be opposite the spaces between those of the other block, a screw detachably connected with one of said blocks, and a spring for moving this block in one direction, substantially as specified.

In testimony whereof I have signed my name to this specification in the presence of two subscribing witnesses.

JOHN A. PEER.
